FIG. 1

FIG. 2

FIG. 3

FIG. 4

INVENTOR

John J. Banigan

Henry Harrold Jr.

ATTORNEY

UNITED STATES PATENT OFFICE.

JOHN J. BANIGAN, OF PROVIDENCE, RHODE ISLAND.

GOLF TEE.

Application filed June 1, 1925. Serial No. 34,042.

To all whom it may concern:

Be it known that I, JOHN J. BANIGAN, a citizen of the United States, residing in the city of Providence, county of Providence, and State of Rhode Island, have invented a new and useful Golf Tee, of which the following is a specification.

The purpose of my invention is to provide a portable golf tee which can readily 10 be adjusted to the requisite height, and which will obviate the necessity of forming the tee by hand or otherwise by hand as is commonly practiced, thereby saving both time and trouble and enabling the player to 15 have at all times a tee ready for immediate use, and quickly adjustable to the height most advantageous for the player.

In the accompanying drawings Figure 1 is a top plan view of my invention. Figure 2 is a vertical section taken on line 2—2 of Figure 1. Figure 3 is an elevation of my invention, and Figure 4 is an elevation showing the tee adjusted as to height with a golf ball mounted upon it ready for play.

Like reference letters and numerals indicate like parts where they occur in the drawings.

I construct the tee in the form of a frustum of a cone, as A, from card board or 30 other somewhat flexible material, and curve the lower edge upward and backward to form a rounded base A¹ for the tee. Entirely around said lower edge I cut vertically directed slits a extending upward 35 a distance into the body of the tee, as shown in the several views of the drawing.

In order to adjust the tee as to height it

is depressed causing the slits a to open out and allow the lower slotted portion of the tee body to spread out fan-like thereby ensuring a more stable base for the tee. The rounded lower edge of the tee will not dig into the ground when the tee is depressed but will slide easily along as the slits open outward, (Fig. 4), and allow the lower edge to spread out freely and thereby form broader and more firm support for the superimposed golf ball. (Fig. 4.)

I claim as my invention and desire to secure by Letters Patent:

1. A golf tee constructed of card board or other flexible material in the form of a hollow frustum of a cone and provided with an upwardly and backwardly turned lower edge, and with vertically directed slits extending upward into the body of the tee and arranged and adapted when the tee body is depressed to open out and allow the lower portion of the tee body to spread out fan-like to thereby afford a stable support for a golf ball.

2. A portable golf tee constructed in the form of a frustum of a cone and having walls adapted to be depressed at will to vary the height of the tee, said walls provided with vertically directed slits disposed in the lower portion of said walls and spaced a distance apart from each other and arranged and adapted to open out when the walls are depressed and allow the lower portion of the tee to flare outward and thereby broaden the supporting base of the tee.

JOHN J. BANIGAN.
